REFLECTOR LAMP

Norman W. Bosten and Morris Solomon,
Los Angeles, Calif.

Application January 16, 1942, Serial No. 427,008

2 Claims. (Cl. 240—61.12)

This invention relates to a lamp structure, and more particularly to a compact, portable device that casts a powerful concentrated beam, and that may be used as a signaling light.

This application is a continuation in part of an application filed on October 13, 1941, in the names of Norman W. Bosten and Morris Solomon, under Serial No. 414,706, and entitled "Reflector lamp."

In said prior application, there is described and claimed a combination of a resilient enclosure or housing, and an incandescent lamp in the housing, arranged so that the front wall of the lamp forms a lens and the rear wall forms a reflector. The structure also included a handle or grip attached to the housing, and appropriate switching means for controlling the energization of the lamp.

It is one of the objects of this invention to improve in general, the structure described in said prior application.

It is another object of this invention to make it possible effectively to use the device as a signaling medium, as by the provision of a conveniently located push button switch.

The intense illumination projected by the device is particularly advantageous for use by airplane pilots. When the fuselage has a front glass visor or shield, the illumination is somewhat dispersed by the glass, especially when the lamp is held at a distance from the window. It is another object of the invention to make it possible to reduce this loss of illumination. For this purpose, the device is arranged to be directly supported on the inside surface of the glass, as by a rubber suction hood attached to the lamp. This hood has the additional advantage of preventing the flow of light to the interior of the plane. And the hood is made sufficiently resilient to provide for aiming of the beam without disturbing the supporting function of the hood.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best defined by the appended claims.

In the drawing:

Figure 1 is a front elevation, partly broken

away, of a lamp structure embodying the invention:

Fig. 2 is a pictorial view from the rear of the structure illustrated in Fig. 1;

Fig. 3 is a sectional view taken along the plane 3—3 of Fig. 2, illustrating the lamp in appropriate supported position on a glass window or shield;

Fig. 4 is a detailed sectional view taken along plane 4—4 of Fig. 2;

Fig. 5 is a fragmentary sectional view taken along plane 5—5 of Fig. 3; and

Fig. 6 is a wiring diagram of the lamp.

The lamp structure includes a lamp unit 1 and a cover 2 therefor. The lamp unit 1 is of the sealed beam type. This sealed beam type of unit includes a glass envelope, the rear wall 3 of which is curved to form an internal reflecting surface 4. The front of the lamp unit 1 is formed with a convex translucent refractor or lens 5. The conductors to a filament in the unit 1 are sealed through the rear of the wall 3.

A flange 7 encircles the body of the unit 1 adjacent the translucent portion 5. It forms the place where parts of the glass envelope are joined together in sealing relationship. This flange 7 is in the form of an annular ring defining shoulders with the adjacent cylindrical portions 8 and 9 of the envelope.

In order to provide a practical support and cover for the sealed beam unit 1, the cover member 2 is made of relatively thin resilient rubber. This cover member 2 closely contacts the external surface of the wall 3. It is also provided with an annular band portion 10 integrally joined to the main portion of the cover 2 and shaped to conform with the external surfaces of the flange 7 and of the cylindrical portions 8 and 9. This resilient cover 2 can thus be slipped over the unit 1 and this unit will be held firmly and resiliently in place by the engagement of the flange 7 with the band 10.

The lamp structure may be effectively used by airplane pilots to signal by the aid of light while the airplane is in flight; or for finding or illuminating objects exterior of the airplane. Under such circumstances it is highly desirable that the interior of the plane be left unilluminated and also that illumination from the lamp 1 be not dispersed or otherwise dissipated through the envelope window.

In order to effect this result, use is made of a resilient rubber bell or hood 31. This bell 31 is adhered over the flange 10 of cover 2. The bell or hood 31 is of general cylindrical form and made of readily yieldable rubber. Any appro-

priate adhering means can be employed between the contacting parts of the bell or hood 31 and the flange 10.

As shown in Fig. 3, the bell or hood 31 has a front edge so that it can be held by suction on the inside surface of the glass pane 32, as for example the observation window of the airplane. The hood thus seals the space defined by it and the housing 2, rendering the suction effective. The hood is furthermore capable of being distorted as illustrated by the dot and dash lines of Fig. 3 so as to permit aiming the beam of light, by appropriate manipulation of a handle or grip, to be hereinafter described.

The bell or hood 31 thus serves effectively to prevent transmission of illumination toward the rear of the device. All of the illumination is confined to the beam which is projected through the window 32.

The rear portion of the cover 2 is extended as a generally cylindrical housing 11 shown most clearly in Figs. 2 and 3. This cylindrical housing extends over the binding post supporting structure 12 firmly attached to the rear of unit 1, and made of insulation material. Through this structure 12 extend the conductors that are sealed through the wall 3 for the filament. They are in turn attached to binding posts, one screw 13 of which is indicated in Fig. 3.

The cylindrical housing portion 11 also serves to support a control switch 14 placed adjacent the rear wall 15 of the housing member 11. This switch 14 is appropriately connected to control the circuit of the filament. It has a threaded shank 16 extending through an appropriate clearance aperture in the rear wall 15. A knurled nut 17 is threaded over the shank 16 in order to hold the switch 14 in place. A manually manipulable element 18 extends from the shank in a well understood manner, capable of being rocked in either of two directions for closing or opening the switch. This member 18 can readily be operated by the fingers of a user who may, as hereinafter explained, support the entire unit by the hand.

It is often desirable to make it possible to energize and deenergize the filament of lamp 1 more rapidly than would be possible by the aid of the manually operable member 18. This is especially useful if it is desired to flash the lamp in definite sequence for signaling purposes.

Accordingly for this purpose a supplemental finger button switch 33 is supported in the top wall of the cylindrical portion 11. As shown most clearly in Fig. 6, this push button switch parallels the switch 14. By alternate depressing and release of the button of this switch, light signals can be transmitted. The button is normally held in open position by spring pressure, in order that a definite force must be imposed on the control button to keep the lamp circuit closed.

As shown most clearly in Fig. 3, the barrel of the switch 33 can extend through the cylindrical portion 11 and its terminals are then available for connection to the other elements of the system.

The entire lamp structure may be supported by the aid of a hand grip 19. This hand grip is shown as extending below the housing portion 11. The grip may be formed as a conveniently formed pistol grip, also molded from rubber. It may be joined to and supported by the cover 2 by the aid of a cylindrical projection 20 (Figs. 3 and 5) extending into an appropriately formed aperture 75

21 in the lower portion 22 of the housing 11. This lower portion 22 may be thickened for the accommodation of the projection 20 as indicated in Fig. 5. Appropriate adhesion may be secured between this portion of the grip 19 and the cover 2.

External leads for completing the circuit of the lamp extend through the grip 19. The grip 19 is provided with a longitudinal aperture 23 extending entirely through the projection 20 and substantially to the bottom of the grip 19. This aperture is lined by a thin metallic tube 24. The interior passage of the tube 24 connects with a transverse passageway 25 extending from beneath the tube 24 to the exterior side wall of the grip 19. The insulated conductors 26 leading from the binding posts supported on the member 12 pass through the tube 24 and thence outwardly through the aperture 25. They may be connected in a well understood manner to a source of electrical energy.

While the operator holds the device for ready manipulation by the aid of the hand grip 19, one of his fingers can readily manipulate the operating member 18 of the control switch 14, or the push button switch 33.

To facilitate proper aiming of the light beam, a sight 34 may be provided. This is shown as comprising a radially extending post or lug 35 formed integrally with hood 31, near its rear edge. The upper surface of post 35 is provided with a diametral notch or groove 36 which is parallel with the light beam from lamp 1. By sighting along notch 36 and directing it toward a desired point, the light beam will be directed correspondingly toward that point.

What is claimed is:

1. In a portable lamp structure, an electric lamp of the incandescent filament type, said lamp having a sealed envelope through which leads for the filament are sealed, a surface of the envelope forming a reflector for the direct rays of light from the filament, and said envelope having a translucent portion opposite the reflector, through which portion light rays from the envelope may be transmitted, a resilient rubber cover closely fitting and resiliently contacting said envelope over the region of said reflector, as well as over the front edge region of the envelope, a grip extending from the cover, and a hood of resilient rubber extending completely around the cover and carried thereby, and projecting forwardly of the translucent portion of the envelope, said hood having a forward edge capable of contacting a wall surface, said hood being so connected to the cover that contact of said edge with a wall surface can provide a fluid sealed space formed by the wall, the hood, and said translucent portion, said hood having flexibility sufficient to permit alteration of the direction of illumination without breaking the seal.

2. In a portable lamp structure, an electric lamp of the incandescent filament type, said lamp having a sealed envelope through which leads for the filament are sealed, a surface of the envelope forming a reflector for the direct rays of light from the filament, and said envelope having a translucent portion opposite the reflector, through which portion light rays from the envelope may be transmitted, there being a flange extending around the envelope adjacent the translucent portion, a resilient rubber cover closely fitting and resiliently contacting said envelope over the region of said reflector, as well as over said flange, a grip extending from the rear of the cover, and a hood of resilient rubber

2,334,899

attached to said cover and extending completely around the flange-contacting portion of the cover, and projecting forwardly of the translucent portion of the envelope, said hood having a forward edge capable of contacting a wall surface, said hood being so connected to the cover that contact of said edge with a wall surface can provide a

fluid sealed space formed by the wall, the hood and said transparent portion, said hood having such flexibility as will permit moving the envelope by aid of the grip to alter the direction of illumination without breaking the seal.
